UNITED STATES PATENT OFFICE.

WILLIAM B. S. REED, OF BROOKLYN, NEW YORK.

OPERATING MECHANISM FOR RAILWAY-SWITCHES.

SPECIFICATION forming part of Letters Patent No. 334,612, dated January 19, 1886.

Application filed September 27, 1884. Serial No. 144,116. (No model.)

To all whom it may concern:

Be it known that I, WILLIAM B. S. REED, of Brooklyn, in the county of Kings and State of New York, have invented certain new and 5 useful Improvements in Operating Railway-Switches, of which the following is a full, clear, and exact description.

My invention consists in improved mechanism for operating railway-switches from 10 switch-houses in situations where there are numerous converging lines of rails, the object being to insure safety by preventing the possibility of mistakes, and also to lock the switches securely either open or closed. To 15 these ends I provide the hereinafter described mechanism, whereby but a single lever is used, and such lever is inoperative to open more than one switch or system at a time or to open another while one remains open.

Reference is to be had to the accompanying 20 drawings, forming part of this specification, in which similar letters of reference indicate corresponding parts in all the figures.

Figure 1 is a general plan view of the switch-operating mechanism as applied to two connecting double lines of rails. Fig. 2 is a vertical section of the operating-stand and mechanism. Fig. 3 is a vertical section at right angles to Fig. 2, and Fig. 4 is a section on line 25 xx of Fig. 3. Fig. 5 is a detail view of the lock devices.

Referring to Fig. 1, the movable switch-points a and their operating rods or bars b are of usual arrangement. At the side of each 35 switch a three-armed lever, c , is pivoted for movement in a horizontal plane, and has one of its arms jointed to the outer forked end of switch-bar b , while to the opposite arm of this lever c is jointed a rod, d . For purposes hereinafter indicated, the pin or bolt connecting 40 the lever to bar b passes through a slot in the bar, so that the lever may move a short distance before operating the switch. The third arm of the lever c is jointed to the end of a 45 dog, e , that is fitted to slide between guides on a plate, f , which is bolted securely to the ties, and the plate f is made with a double-inclined projection, f' , which, in connection with a recess in the under side of a dog, e , 50 (see Fig. 5) causes the dog e to rise at its outer end at the first movement of lever c , thereby clearing the dog from a projection, b' , on the

lower arm of bar b , so that the further movement of the lever may operate the switch. The dog falls again when the switch is fully 55 opened or closed, thus locking the switch, and it is to be observed that this lock relieves the operating mechanism of all strain.

In connection with each switch there is a detecting-bar, h , hung by arms or links at the 60 side of one rail, so as to be raised above the level of the rail by the connecting-rod g from lever c while the switch is being either opened or closed. This bar h is of such a length to extend from one truck of a car to the other, 65 so that an attempt to move the switch until a train has entirely passed will be prevented by the car-wheels holding the bar h down.

The connecting-rods d from the several switches all pass to the operating-stand A, the 70 construction and arrangement of which is shown in Figs. 2, 3, and 4, and is as follows:

i is a vertical shaft supported by an upper plate, k , and lower plate, k' , and carrying a gear-wheel, l , which is attached by grooves 75 and feathers, so as to be free to move up and down on the shaft.

m is a second vertical shaft carrying a number of segment-gears, n , loose thereon in position for being engaged any one of them with 80 gear-wheel l as the latter is raised or lowered. At third shaft, o , carries segment-gears n' , similarly arranged with reference to gear-wheel l , and I remark that the number of shafts and number of segments on each will vary according to the number of switches to be operated from the stand. Each segment n is formed with an arm, p , connected to one of the rods 85 d , that pass to the switch-levers.

q is a lever or handle fixed on the upper 90 end of shaft i , and extending to and resting on a raised supporting-plate, r .

s is a lever furcured at s' , whose inner end is forked and engages a groove in the hub of gear-wheel l , and whose outer end extends beneath a horizontal slide-rod, r' , fitted beneath plate r . The rod r' has an arm, s^2 , which is slotted horizontally to receive the lever s , so as to hold the same in position as moved up or down. The slots correspond to the number of segment-gears n ; consequently the lever s being held in one slot the gear-wheel l is engaged with one segment n and its corresponding segment n' . The slide-rod r' is held in 95 100

position to retain lever s by a spring, t , and on the rod is an arm, t' , projecting upward through plate r into a position for being moved by handle q , when the latter is moved on plate 5 r' far enough to close the switch. The result of this arrangement is that lever s cannot be moved while engaged with the slotted arm of rod r' , and the handle q can be used to move rod r' only when the handle is moved to the 10 closed-switch position. The possibility of error is thus practically eliminated. The gear-wheel l has a vertical plate, u , sliding through upper plate, k , and numbered to show the position of the gear-wheel.

15 Each switch-rod d has suitable connections, w , to signals for operating the signals simultaneously with the switches, and the segments n' , as shown, also operate signals by their arms p' .

20 In place of using segment-gears, as shown, there may be simple interlocking arms used on the shafts.

In some systems it may be necessary to open 25 two switches at once by one movement of the lever, which can be done by suitable connections, and I do not limit myself in that respect.

Having thus described my invention, I claim as new and desire to secure by Letters Patent—

1. In a railway - switch, the combination, 30 with switch-bar b and the three-armed lever c , having one of its arms connected to said bar,

of the locking-dog e , connected to the arm of the said lever, which projects at right angles to the other two arms, the detecting-bar h , and the rod g , connected to the detecting-bar and 35 to the arm of the lever to which the dog is pivoted, substantially as herein shown and described.

2. In a railway-switch, the combination of a series of segment-gears, n , having connections for operating separate switches, a gear-wheel fitted for adjustment on a shaft to engage either segment, and a lever or handle connected to the shaft for turning the gear-wheel, substantially as described. 40

3. The shaft i , adjustable gear-wheel l , shaft m , segment - gears n , switch - rods d , handle q on shaft i , and lever s , connecting to wheel l , substantially as described, combined for operation as specified. 45

4. The slide - rod r and its slotted arm s^2 , combined with lever s , and gear-wheel l , adjustably for operating either switch of a series, substantially as described.

5. In a switch, the slide-rod r' , having arms $s^2 t'$, spring t , switch-moving lever q , and lever s , combined for operation substantially as described. 50
